William H. Racey

UNITED STATES PATENT OFFICE

WILLIAM H. RACEY, OF NEW YORK, N. Y.

BURNER FOR VAPOR-LAMPS.

Specification of Letters Patent No. 25,525, dated September 20, 1859.

To all whom it may concern:

Be it known that I, WILLIAM H. RACEY, of the city, county, and State of New York, have invented a new and Improved Lamp; and I do hereby declare that the following is a full, clear, and exact description of the same, reference being had to the annexed drawings, making a part of this specification, in which—

10 Figures 1 and 2, are vertical central sections of my invention, the two planes of section crossing each other at right angles.

Similar letters of reference indicate corresponding parts in the two figures.

15 This invention relates to an improvement in a lamp for burning without a chimney these hydro-carbons that contain an excess of carbon, and for which Letters Patent were granted to me bearing date June 29th, 1858.

20 The object of the within described invention is to obtain a lamp far more portable than the patented lamp above referred to and still one that will operate or burn the material aforesaid more perfectly and with 25 a more persistent flame.

To enable those skilled in the art to fully understand and construct my invention I will proceed to describe it.

20 A, represents a cap which is screwed into the upper end of the lamp and B, is a wick tube which is of the usual rectangular form, passes through the center of the cap and extends a requisite distance above the cap A. The wick tube B, is encompassed by a 35 tube C, which is of slightly conical form and extends a short distance above the upper end of the wick tube. The lower end of the tube C, has a curved flanch a, attached to or formed on it. This flanch is curved upward

40 all around the base of the tube and it is perforated as shown at b. The cap A, is also provided with a similar flanch c, which is bent or curved upward, the two flanches being connected at their outer edges entirely around or at certain points d', and forming the attachment between the tube 45 C, and the cap A, and also forming an annular chamber d, all around the base of the tube, the perforations b, with spaces b', be-

50 tween the points d', forming the only communication between the lower end of tube C, and the external air.

On the upper end of the tube C, a cap D, is fitted. This cap is of the usual dome-shape and has a slot e, made in its upper end, said slot extending from one side of the

cap to the other as shown in Fig. 1. Within the cap D, a smaller cap E, is secured, the upper part of which approximates in form to the upper part of the cap D, and it is also provided with a slot f. The upper part of the cap E, however is slotted laterally at opposite sides of its slot f, as shown at g, g, Fig. 2, said slots extending nearly if not quite the whole width of the cap. 60 The lower part of the cap E, is of inverted conical form, as shown clearly in both figures and it is attached to the cap D, by horizontal plates h, h, said plates being secured to a cylinder f', which is fitted within a 70 cylinder g', to which the upper part of the cap E, is attached by plates h', the plates h', h', being in the same plane with slot e, below each end of it.

75 Within the lower inverted conical portion of the cap E, a burner F, is placed. This burner is of oval form and is equal in length to the diameter of the lower part of the cap E, and fits snugly within it. The upper edges i, of the burner are of rounded 80 form as shown clearly in Fig. 1, and its lower edge is flush with the lower edge of cap E. The lower edges of the cap E, and the burner F, are a trifle above the upper end of the wick tube B, a space j, being allowed between, as shown clearly in both figures.

G, G, represent two curved or arched rods which extend entirely over the slot f, of the smaller cap E, and at a point between the 90 slot f, and the slot e, of cap D. The ends of these rods are attached to the plates h', of the upper part of the cap E. The rods G, G, as well as the burner F, are constructed of copper. 95

I prefer to have the burner F, for reasons hereinafter stated, perforated. This burner it will be seen by referring to Fig. 1, has its upper part wider than its lower part, or, it may be described as expanding gradually 100 in a longitudinal direction from its lower to its upper end, and transversely it would be preferable to have it gradually contracted from its lower to its upper end, as shown in Fig. 2.

105 The operation is as follows:—The wick H, is lighted at the upper end of tube B, and a gas-generating flame a*, produced in consequence of an imperfect supply of oxygen, it being understood that the flame is encompassed by the burner F, which excludes the requisite supply of oxygen sufficient being 110

admitted at the space *j*, to support an imperfect combustion. In consequence of this imperfect combustion hydro-carbon gas is eliminated and passes up through the burner 5 F, and is allowed to gradually expand, said gas passing through the slots *f*, *e*, of the caps E, D and burning with an illuminating flame *b*^x, at the slot *e*, of the cap D. The copper rods G, G, perform two functions, they, in 10 common with the burner F, have a tendency to spread or expand the flame thereby presenting a greater surface of flame to the air, and they also divide the mass of heated air into parts so that the same will be brought 15 in contact with the flame in a more heated and in different positions producing at the same time a permanent rarefaction and consequent draft in tube C, so that the flame, will receive a greater amount of oxygen, and 20 the rods also serve to keep the air in a rarefied state. The burner F, also serves to rarefy the air within the caps and the two caps D, E, cause the air to impinge against the hydro-carbon gas and flame at different 25 points. The slots *g*, *g*, in the smaller cap E, also cause a current of air to impinge against and become incorporated with the gas below 30 the top of cap E. The employment or use of the caps D, E, in connection with the burner F, and rods G, G, enable me to obtain a perfect illuminating flame *b*^x with a comparatively short tube C, for by the use 35 of the caps, burner and rods a good and sufficient draft is obtained through the tube and made to impinge in the most advantageous manner against the flame.

In order to use the lamp the wick H, is lighted and a gas generating flame *a*^x, ob-

tained, the oxygen being admitted to it in small quantities in consequence of the close 40 proximity of the burner F. The flame *a*^x, eliminates a hydro-carbon gas which escapes up through the burner F, slots *f*, *e*, and burns with an illuminating flame *b*^x, at *e*. When the gas is produced the wick H, is 45 gently raised until the gas is ignited at *e*, the flame *a*^x, producing such result in consequence of the perforations in the burner F, which aerifies the gas and permits the flame *a*^x, to ignite it. Were the burner F, not 50 perforated, an auxiliary flame or light would be required to ignite the gas at the slot *e*, and the aerifying of the gas also increases the power and rarefied development of the illuminating flame. Hence the advantage 55 of having the burner F, perforated.

I do not claim a plurality of caps D, E, to deflect the air and cause it to impinge against the flame. Neither do I claim the curved flanches *a*, *c*, at the bottom of the 60 tube C, and on the cap A. Nor do I claim separately and irrespective of arrangement a heatconducting rod or wire G; but

Having thus described my invention what I do claim as new and desire to secure by 65 Letters Patent, is,

The burner F, and curved rods G, G, one or more, in combination with one or more deflecting caps D, E, and draft tube C, arranged for joint operation substantially as 70 and for the purpose set forth.

WILLIAM H. RACEY.
